(57) **CLAIM**

The ornamental design for a combination ceiling fan and light fixture, as shown and described.

DESCRIPTION

FIG. 1 is a perspective view from below of a combination ceiling fan and light fixture in accordance with my design; FIG. 2 is a reduced top plan view of the combination ceiling fan and light fixture in accordance with my design;

FIG. 3 is a reduced bottom plan view of the combination ceiling fan and light fixture in accordance with my design; FIG. 4 is a front elevation view of the combination ceiling fan and light fixture in accordance with my design; and, FIG. 5 is a side elevation view of the combination ceiling fan and light fixture in accordance with my design.

FIGS. 4 and 5 are identical except for the positioning of the fan blades.

The lines indicating shading in FIGS. 1-5 are for illustrative purposes only and form no part of the claimed design.

The broken line showing of environmental structure is for illustrative purposes only and forms no part of the claimed design.
